CLAIM

The ornamental design for the light hanging tool, as shown and described.

DESCRIPTION

FIG. 1 is a front elevational view of a light hanging tool showing my new design; the vertical shaft of the light hanging device is shown broken away to indicate indeterminant length;

FIG. 2 is a elevational view thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is a perspective view thereof.
